UNITED STATES PATENT OFFICE.

JAMES MAIRON COOPER, OF McLEANSBORO, ILLINOIS.

CULVERT-FORM.

1,163,640.

Specification of Letters Patent. Patented Dec. 14, 1915.

Application filed May 15, 1912. Serial No. 697,477.

To all whom it may concern:

Be it known that I, JAMES M. COOPER, citizen of the United States, residing at McLeansboro, in the county of Hamilton and State of Illinois, have invented certain new and useful Improvements in Culvert Forms, of which the following is a specification, reference being had therein to the accompanying drawing.

This invention relates to an improvement in culvert forms for molding concrete culverts, and one of the objects of the present invention is the provision of a form of this character which, when not in use, can be readily knocked down and stored in a compact space to facilitate storage and transportation thereof.

A further object of the present invention is the provision of a form of this character which can be adjusted to various sizes, thus enabling the same form to be used in the molding of culverts of different sizes.

A further object of the present invention is the provision of a culvert of this character comprising a casing which is formed of a plurality of detachably connected sections, in combination with improved means for holding the casing distended.

Other objects of the invention will be apparent from the detailed description hereinafter when read in connection with the accompanying drawings forming a part hereof, wherein a convenient embodiment of the invention is illustrated, and wherein like characters of reference refer to similar parts in the several views.

In the drawings: Figure 1 is an end view of a culvert form constructed in accordance with the present invention: Fig. 2 is a side elevation, parts being shown in section, and Figs. 3, 4, 4^a, 5, 6 and 7 are detail views.

Referring now more particularly to the drawings, A designates the casing of the form which is formed of sheet metal and is, when the form is in its set up position, substantially circular in cross section. The casing A is formed of a plurality of sections, the adjacent edges of which are detachably connected to each other so that the sections may be disengaged from each other when the form is knocked down. In the embodiment of the invention illustrated, the casing A is formed of four (4) sections A', A², A³ and A⁴. As above stated, the adjacent edges of the sections of the casing of the form are provided with means enabling the sections

to be detachably connected with each other. In practice, the adjacent edges of the sections of the casing overlap and the means for detachably connecting the edges of the sections are preferably of such a nature that the amount which the sections overlap can be varied so that the diameter of the completed form can be varied to a very great extent if desired.

In the embodiment of the invention illustrated, each of the sections of the culvert is provided along one edge thereof with a plurality of rows of elongated openings a therein, and along its opposite edge with a row of buttons a' rotatably supported therein, which buttons are provided with elongated heads of a size to pass through the openings in the edge of the adjacent section. To assemble the sections of the casing A of the form the buttons a' of each section are introduced through the opening a in the adjacent edge of the next section, and are then given a quarter turn, thus locking the sections together. Manifestly by providing in each section a series of rows of openings a, studs of the next adjacent section can be secured in any one of said rows, thus enabling the diameter of the completed casing to be varied to any desired extent. The studs a' may be of any well known construction. In practice, however, I prefer to rigidly secure in one edge of each of the casing sections a row of rivets a² which are provided with portions a⁴ which project inwardly of the sections and upon which are rotatably mounted the elongated button heads a⁵.

After the sections of the form have been connected to make a form of the desired diameter, internal bracing means are employed for giving the desired contour to the casing. For this purpose, a plurality of expandable rings B are utilized bracing members being employed in connection with each of said rings for forcing the same tightly into engagement with the inner surface of the casing A. Each of the rings comprises a split ring of spring metal, the ends of which overlap, said rings being normally contracted to the size of a circle equal to the cross section of the smallest culvert which can be made with the casing A and being expandable to a size to fit within the largest culvert which can be made with the casing A. Employed in connection with each of the expandable rings B are a plurality of adjustable brace

members which are adapted to expand the rings a sufficient extent to cause the same to tightly engage the interior of the casing of the form.

5 In the embodiment of the invention illustrated, three braces are utilized for connection with each expandible ring, namely, a brace F, a brace F', and a brace F². The brace F comprises two members f and f' which are pivotally connected adjacent the inner ends thereof and which are provided at the outer ends thereof with laterally extending portions f², the outer surfaces of which are provided with grooves therein 10 which are adapted to engage the expandible ring B. The extreme inner end of the member f' is provided with a U-shaped portion f³ which is adapted to fit over the member f of the brace when said members are moved into 15 alignment, and thus limit the pivotal movement of said members in one direction. The U-shaped member f³ is preferably of such a form that it will not engage the member f of the brace until after the member f' has 20 been moved slightly beyond a position in direct alignment with the member f, so that the resiliency of the expandible ring B will hold the brace in its extended position. If desired, means may be provided for 25 positively locking the members of the brace in their extended positions and in the embodiment of the invention illustrated, I have shown the U-shaped member f³ as provided with a set screw which may be actuated to 30 engage the member f of the brace. To vary the length of the brace when extended, means is provided for varying the pivotal connection of the members f and f' of the brace. To this end, the member f' of the 35 brace is provided with a series of elongated holes f⁴ therein, and the member f of the brace is provided with a stud projecting from one face thereof which is provided with an elongated head f⁵ which is of a size 40 to pass through the elongated openings in the member f of the brace. Obviously by securing the stud of the member f in any one of the openings of the member f' of the brace, the length of the brace may be varied 45 to any desired extent. The brace F' is similar in construction to the brace F just de-

scribed, except that the members thereof are provided at their upper ends with laterally projecting portions e which are grooved for the reception of the expandible ring and 55 which extend in an opposite direction to the laterally projecting portions f² of the brace member F. Owing to this construction, when the braces F and F' are secured within the expandible ring in crossed position, there is provided therebetween a space in which is positioned the third brace F². The brace F² is similar in construction to the braces F and F' except that no laterally projecting portions are provided at the end thereof, the 60 grooves for the reception of the expandible ring being in this instance formed directly in the ends of the brace. One end of the brace F² is provided with two grooves so as to receive the overlapping ends of the expandible ring B. In practice, as many expandible rings B and braces therefor may be used as is found desirable.

While a convenient embodiment of the invention is illustrated in the accompanying 75 drawings, it will be understood that many changes may be made to the particular form and construction therein shown without departing from the spirit and scope of the invention as defined in the appended claim. 80

I claim:—

In a culvert form of the character described, the combination with a knock down tubular metal casing, of means for holding the metal casing extended, said means comprising a separate expandible ring adapted to be placed within the casing and expanded into direct frictional engagement therewith, and a plurality of adjustable braces for expanding the ring and maintaining the same 85 in engagement with the interior of the casing, said braces being provided with offset 90 end portions adapted to slidably engage the ring at separate points around the same, said portions having grooves to receive portions 95 of the ring therein.

In testimony whereof I affix my signature in presence of two witnesses.

JAMES MAIRON COOPER.
